TURNING MACHINE AND METHOD

Walter J. Beattie, Cohoes, N. Y., assignor to The
Beattie Manufacturing Company, Cohoes, N. Y.,
a corporation of New York

Application April 7, 1933, Serial No. 665,022

22 Claims. (Cl. 223—38)

The present invention relates to a method and apparatus intended for folding and pressing the edges of collar or other blanks, and for suitably marking the folded blank by indenting or pressing the edge of the blank inwardly as distinguished from embossing the blank surface.

The principal object of the invention is to provide a method and machine which will form a collar or other blank by infolding and pressing its edges over a forming die and mark the blank after it has been folded, preferably by indenting its edge in a direction in the plane of the forming die and blank and inwardly from the blank edge.

I am aware of machines which mark a blank of material by providing cooperating recesses and protuberances on the forming die and on the bed, these and similar machines serving to emboss the surface of the blank. The distorted surfaces of either the forming die or bed of these machines prevent the formation of a uniform fold and result in a blank having its surface embossed. However, the present method and apparatus are fundamentally distinct, in that a uniformly infolded blank is produced and thereafter the folded edge is properly indented or marked, without embossing the surfaces.

Another object of the invention is to provide an apparatus which will infold and indent collars or similar blanks of various sizes and shapes.

A particular use of such indentations on the blank is for assembling purposes. In assembling collars, that is, in stitching the collar top to the blank, it is convenient to have on the blank indicia denoting where the ends of the top should be attached. I have found it expedient to place these indentations on the upper edge of the blank near the ends thereof.

In stitching the blank carrying the collar top to the shirt collar band, it is also desirable to have indicia on the lower edge of the blank near the ends thereof at points which will conform to the front opening seam of the shirt.

In addition, a similar indentation on the lower edge of the blank at the center thereof is advantageous for assembling purposes.

Chalk marks, or marks stitched in the blank have not proved suitable, and I have found that a mark or indent made in the blank edge while the blank is on the forming die, but after the folding and pressing operations, as by a finger moving into a recess in the forming die, will mark the blank in a sufficiently permanent manner. By providing mechanism carried entirely by the die head to indent the infolded blanks, it

is possible to use a plane surfaced bed plate and thus insure more perfectly and uniformly folded blanks. Furthermore, a mark made with such mechanism can be placed with exactness after the edge of the blank has been folded uniformly. 5

Various novel features in the apparatus employed to accomplish these objects and practice the method will be obvious from the description of one embodiment thereof illustrated in the accompanying drawings wherein:

Figure 1 is a transverse vertical sectional view of the machine, showing the die head in elevated position.

Figure 2 is a transverse vertical sectional view of the bed plate and die head, showing details of 15 the finger operating mechanism.

Figure 3 is a front view of the die head.

Figure 4 is a top plan view of the die head.

Figure 5 is a transverse vertical sectional view of the die head showing a portion of the bed. 20

Figure 6 is a horizontal sectional view of the die head taken on line 6—6 of Figure 5, the forming die being contracted.

Figure 7 is a half transverse vertical sectional view of the die head and a modified form of finger fitting, and

Figure 8 is a horizontal section on line 8—8 of Figure 7, showing a modified form of forming die blade, and its cooperation with a modified form of finger.

Referring more particularly to the drawings, I designate the die head with its forming die 10, which is carried by the arms 11 fixed to a shaft 12 at the back of the machine, said shaft being supported by the machine frame. Through the 35 hollow working table 13 of the machine, a bed 2 is adapted to move vertically. Infolding dies 3, 3' are mounted for lateral movement across the bed.

When a blank of material is placed on the 40 heated bed, and the forming die lowered thereon, the infolding dies are moved in over the edges of the forming die to infold the edges of the material over the forming die, and the bed is elevated slightly to crease the folded edges, 45 all in a manner well known in the art. When the forming die is elevated, carrying with it the folded blank, fingers carried by the die head are caused to move into recesses in the edges of the forming die to indent the folded edge of the 50 blank in a direction inwardly from the edge of the forming die in a manner hereinafter described.

In Figure 3 the forming die 10 is shown as comprising end sections 14 and 16 and a central sec- 55

tion 15; rigidly carried respectively by forming die section carriers 17, 19 and 18. Forming die sections 14 and 16 have in one edge thereof substantially semi-circular recesses 25 and 26, respectively, each adapted to cooperate, as shown in Figure 6, with one of a plurality of fingers 27, when the fingers are moved into the recesses in the manner hereinafter described, to indent and form indicating indentations or impressions on the folded edge of the blank. These impressions serve to denote the points on the blank where the ends of the collar top are to be attached.

The opposite edges of sections 14 and 16 are provided with substantially semi-circular recesses 28 and 29, respectively, each adapted to cooperate with a finger 27, when the fingers are moved into the recesses in a manner hereinafter described, to indent and form indicating indentations or impressions on the folded edge of the blank, these marks denoting the points of attachment of the blank carrying the top to the shirt collar band at the front opening seams.

Section 15 has in one of its edges a similar recess 30 to cooperate with one of the fingers to form an indicating indentation in the folded edge of the blank of material at the center thereof.

The central section carrier 18 is fixedly mounted to an angle bar 31, while as shown in Figures 3 and 5, section carrier 19 is adjustably carried by the angle bar 31, the latter being rigidly secured to the top plate 32 by bolts 33. Carrier 19 may be adjusted longitudinally along angle bar 31 by means of bolts 34 passing through slots 35 in the angle bar, and threaded into spaced apertures 36 in carrier 19. This adjustment serves to regulate the length of the forming die for various collar sizes.

Carrier 17 is adjustably mounted on an angle bar 37 in the same manner as is carrier 19 to angle bar 31, but angle bar 37 is movably attached to top plate 32 by means of bolts 20 provided with washers 21, said bolts passing through slots 22 in the top plate 32, and being threaded into apertures in angle bar 37. This movement is longitudinal of the top plate 32, and is controlled by the pressure of spring 38, which extends between and is secured to angle bars 37 and 31.

As shown in Figure 3, portions 39 and 40 of the inner end surfaces of angle bars 37 and 31, respectively, are adapted to cooperate with a cam 47 to expand the forming die in a manner hereinafter described.

Referring to Figures 2 and 4, a bent arm 41 is pivoted on a pin 42 mounted in brackets 43 attached to an extension 44 of the working table 13; this arm is secured adjustably at its opposite and threaded end 45 to an angular extension 46 of the longitudinally tapered cam 47 by means of nuts 48; said threaded end passing through an aperture in the angular extension 46. The cam 47 has a tapered portion 47' (Fig. 4) which cooperates with surfaces 39 and 40 to move angle bar 37 carrying forming die section carrier 17 endwise away from angle bar 31 and forming die section carrier 19, to expand the forming die when the die head is being lowered. The retraction of cam 47 when the head is elevated permits spring 38 to return angle bar 37 toward angle bar 31 to contract the forming die. The action of cam 47 is timed to the action of the indenting fingers 27, as will be later explained.

The die head top plate 32 is provided with a number of bearing lugs 49 to receive and support finger carrying shafts 55 and 56. Collars 57 having set screws 58 are arranged inside said bearing

lugs, as shown in Figure 4, in order to hold the shafts against longitudinal movement within the bearing lugs, the shafts being free to rotate within the bearings.

In Figure 5 the fingers 27 are shown attached to their carrying shafts, said fingers being substantially circular in cross section and tapered, and provided with outwardly bent portions 59 at their ends. The fingers project from fittings 60 which include a hollow cylindrical portion 61 which embraces the shafts. The fingers, or their supporting fittings, may be suitably recessed to receive an electric heating coil. The cylindrical portion 61 is split as at 62 and, on opposite sides of the split opening, is provided with lugs 63 and 64, said lugs being provided with screw threaded apertures to receive a set screw 65. By reason of this connection, each finger may be adjusted longitudinally along its finger carrying shaft to align it with its cooperating forming die blade 20 recess before setting up on screw 65 to secure it in place. This longitudinal adjustment may be done by eye, or suitable indicia may be provided for this purpose on the finger shafts. It is desirable to have this adjustment to permit cooperation of the fingers with various sizes of forming die blades, or with forming die blades having recesses in different positions. Furthermore, the fingers may be rotated around their carrying shafts before tightening screw 65, in order to regulate the force with which the fingers impinge on the forming die blade in indenting, or to adapt the fingers for use with forming die blades of various contours.

The finger carrying shafts 55 and 56 are rotated through suitable mechanism from rock shaft 12, said shaft being rocked by a depending arm 66, which arm is moved by a cam 104 on the main cam shaft 103 in a manner fully described in my prior Letters Patent No. 1,698,469, granted January 8, 1929.

As shown in Figure 2, an upwardly extending arm 67 is fixed to rock shaft 12. Arm 67 is provided approximately midway of its length with an aperture which forms a bearing for a crank 45 shaft 68, said crank shaft being rotatable within the bearing. The outer end of a connecting rod 71 is pivotally connected to a crank 69 of the crank shaft 68. The inner end of the connecting rod 71 is pivotally connected to a crank 73 by a pin 72. The crank 73 is secured to finger carrying shaft 55 by means of a collar portion 74 and a set screw 75.

A stub shaft 80 is fixed to the extreme upper end of the arm 67, and rotatably mounted on the near end of this stub shaft (as viewed in Figure 2), is a segmental gear 81 having teeth 82. The teeth 82 mesh with the teeth of a pinion 83 fixed to crank shaft 68. The segmental gear 81 is provided with a rearwardly extending arm 84 to which a link 86 is pivotally connected. The opposite end of link 86 is pivoted at 87 to an upward projection 88 of the working table extension 44.

Referring to Figures 3 and 4, finger carrying shafts 55 and 56 carry movable split collars 89 and 90, respectively, said collars being held to their shafts by set screws 91 and 92, respectively. Collar 89 has integral therewith a downwardly extending crank arm 93, while collar 90 likewise carries an upwardly extending crank arm 94. Connecting the ends of said cranks, and pivoted thereto at its ends, is a link 95, said link with cranks 93 and 94 serving to rock shaft 56 in a direction opposite to the direction of rotation of shaft 55 in order to cause the sets of fingers on opposite sides of the die head to impinge on the 75.

forming dies simultaneously, as will be later described.

The action of the edge indenting fingers 27 as the die head is lowered and elevated is revealed in Figure 2, wherein die head positions marked A, B and C are respectively the full elevated, intermediate, and completely lowered positions. The corresponding positions of the crank 69 which actuates connecting rod 71 are, respectively, A', B' and C'. In full elevated position A, at which time the blank of material is placed in position on the bed 2, the crank 69 is at its lowermost position A', and fingers 27 will be completely withdrawn from the forming die. At this position the surface 47' of cam 47 will not be in engagement with surfaces 39 and 40 and the forming die will be contracted.

As depending arm 66 is moved to the right as viewed in Figure 2, shaft 12 is rocked counter-clockwise, this movement serving to lower die head arms 11, and to move arm 67 from right to left. Arm 67 will carry the segmental gear 81 from right to left, and by reason of extension 84 being pivoted to link 86, segmental gear 81 will also move around its shaft 80 in a clockwise direction. The rotation of segmental gear 81, through its teeth 82, causes rotation of pinion 83 and shaft 68 in a counter-clockwise direction, moving crank 69 from position A' toward full line position B'. This movement draws connecting rod 71 to the right, which rocks finger shaft 55 clockwise by means of crank 73, and the finger shaft 56 counter-clockwise through link 95; it will be apparent that such movements of the finger shafts cause the indenting fingers 27 to move into engagement with their corresponding forming die recesses.

During the movement described above, namely, from die head full elevated position A to intermediate position B, the tapered portion 47' of cam 47 has engaged surfaces 39 and 40 to completely expand the forming die at die head position B when the fingers 27 engage their recesses. There being no blank of material on the forming die at this time, no indenting is accomplished.

Further lowering of the die head causes further movement of segmental gear 81, which in the same manner as above, brings the crank 69 to its highest position C', thus causing the indenting fingers to be completely retracted from the forming die when the latter reaches the bed, as shown by die head position C. The fingers being completely retracted, it is apparent that the infolders are free to move in and fold the edges of the blank of material over the forming die without interference from the fingers.

During the above movement of the die head, namely, from position B to position C, cam surface 47' remains completely engaged with surfaces 39 and 40, to keep the forming die completely expanded.

The blank is now infolded and pressed over the forming die, in a manner well known in the art, and after said operation, and in a manner fully described in my prior Patent No. 1,698,469, depending arm 66 is caused to move from right to left to turn rock shaft 12 in a clockwise direction and elevate the die head with its forming die, said forming die now carrying the blank of material 70 infolded over its edges.

The rocking of shaft 12 in a clockwise direction moves arm 67 from left to right, thus carrying segmental gear 81 from left to right, and causing it to rotate around stub shaft 80 in a counter-clockwise direction. Thus pinion 83

with crank shaft 68 is rotated clockwise to move crank 69 from upper position C' toward intermediate position B', drawing link 71 to the right to rock finger carrying shaft 55 clockwise; and finger carrying shaft 56 counter-clockwise through link 95, the movements of the finger carrying shafts tending to move the fingers into their recesses in a direction in the plane of the forming die and blank. When the die head reaches the intermediate position B, it is apparent that the fingers will be forced into the forming die recesses, thus making an indentation on the edge of the blank which is folded over the edge of, and carried by the forming die.

It is to be noted that, upon the die head reaching the intermediate position B on the upstroke of the die head, at which position the fingers are in engagement with their recesses, that cam surface 47' is still completely engaged with surfaces 39 and 40 to retain the forming die in expanded condition.

Movement of the die head from position B to position A will, of course, retract the fingers, and it is during this phase of the die head travel that cam surface 47' is removed from surfaces 39 and 40 to permit contraction of the forming die. The forming die being contracted, the attendant may easily strip the infolded, pressed and indented blank from the die.

As mentioned before, the fingers 27 may be adjusted longitudinally of their shafts for proper positioning with respect to their forming die recesses before operating the machine. This may be done most conveniently when the die head is elevated, and may be done by eye, or by means of suitable indicia on the finger carrying shafts 55 and 56. A suitable hand tool may be inserted between cam surfaces 39 and 40 when the die head is elevated, to expand the forming die to aid in adjustment. In Figures 3 and 4, the forming die is shown contracted as it would be in the full elevated position A, and the recesses 25 and 28 in forming die section 14 are shown disposed a slight distance inside the position of their respective fingers 27; this distance allowing for, and being equal to, the longitudinal distance traversed by forming die section 14 during expansion. Such positioning of fingers 27 with respect to recesses 25 and 28 insures alignment of said recesses with their respective fingers 27 when the forming die is expanded, it being in such condition at the intermediate die head position B, when the fingers engage the recesses to indent the folded edge of the blank.

In Figure 7, a finger construction is shown in which a finger 27 is shown held within the finger fitting 60 by means of a retaining screw 100. Fitting 60 is of hollow construction, having disposed within its hollow body an electric heating coil 101. Referring particularly to Figure 8, a modification of finger and cooperating recess is shown in which a finger 27 substantially triangular in cross-section cooperates with a V-shaped recess in the edge of the forming die blade 10.

In Figure 1, the mechanism for operating depending arm 66 to raise and lower the die head is disclosed, as well as the mechanism for operating the infolding dies 3, 3'. This mechanism is described in my prior Letters Patent No. 1,698,469, granted January 8, 1929, to which reference is made for a complete description thereof. Figure 1 illustrates the mechanism employed in Patent No. 1,698,469, with the addition of 75

means, which will be later described, to operate the additional infolding die 3'.

A brief description will suffice to show the operation of said mechanism.

5 Shaft 103 is a cam shaft, which may be rotated from a source of power in either direction through suitable clutch mechanism. Mounted on said cam shaft is a cam 104, which, when rotated in a counter-clockwise direction, bears against a 10 cam follower roller 105 carried by a pair of lever arms 106, moving said arms from left to right as viewed in Figure 1; this movement also moving depending arm 66 from left to right to lower the die head. The upper ends of arms 106 carry 15 a cam follower roller 107 to engage the adjustable cam face 108 carried by the arm 66.

It will be noted that the cam 104 has an arcuate periphery of sufficient extent to permit continued rotation of the cam shaft in a counter-clockwise direction after the head is lowered, and thus the head will be maintained lowered for a considerable portion of the rotation of the cam shaft; this formation of the cam causing the latter to maintain the head lowered during the 25 succeeding operations which are effected by other cams upon the cam shaft until the direction of rotation of the cam shaft is reversed by clutch mechanism.

The lowering of the head tensions a spring 109 30 which is secured at its upper end to an arm 110, rigid with rock shaft 12, and at its lower end anchored to a cross rod carried by the machine frame. When the direction of the cam shaft is reversed to release the pressure of cam 104 upon 35 lever arms 106, the spring 109 automatically raises the die head.

The construction and operation of the infolding means is described in my prior Patent No. 1,698,469, and the construction and operation of 40 said means in Figure 1 is the same as in said prior patent, with the exception that I now provide two infolding dies with sufficient additional mechanism to operate the same.

The infolding means are shown in Figure 1 as 45 comprising infolding dies 3, 3' carried by infolding die carriers 111, said carriers being connected with slide blocks 112 by means of a plurality of flat links 113. Said flat links are so disposed as to not interfere with the fingers 27 when the 50 latter are retracted when the forming die is lowered onto the bed plate. The slide blocks are formed to receive the eccentric ends of short vertical shafts 114 and 115, extending through bearings in the top of the table 12, and carrying 55 at their respective lower ends bevel pinions 116 and 117, adapted to mesh respectively with bevel segmental gears 118 and 119. Segmental gears 118 and 119 face toward opposite ends of the machine, for a reason which will presently 60 be apparent. The segmental gears 118 and 119 are rigidly carried by rock shafts 120 and 121, which shafts are supported by suitable brackets attached to the machine frame.

Rock shaft 120 is provided with a depending 65 segmental gear 122 fixed thereto, and meshing with a complementary gear 123 of segmental form having secured to one side thereof a cam follower roller 124 which is engaged by a cam 125 on shaft 103 and adapted to be moved in a counter-clockwise direction upon rotation of the cam shaft in order to force gears 122, 123, from left to right, as viewed in Figure 1; this movement rocking shaft 120. Rock shaft 121 will be rocked simultaneously with shaft 120 by reason of a link 126, 70 pivoted at 127 to one side of segment 123, and

linked at 128 to a crank 129 rigid with shaft 121. The cam is of sufficient extent so that it does not completely pass the roller 124, while moving in a counter-clockwise direction, and at the termination of the rotation of the cam shaft in a counter-clockwise direction, the cam is still in engagement with the roller 124 and maintains the infolding dies in advanced position over the material. Upon the reversal of the direction of the cam after completion of the various operations, its engaging 10 surface will pass roller 124, whereupon the spring 130, secured at one end to gear 123, and at its other end anchored by eye 131 to the front of the machine frame, will retract the infolding dies by moving the gears 122, 123 from right to left, as 15 viewed in Figure 1.

Obviously, the details of the preferred embodiment described may be modified materially without departing from the invention.

I claim:

1. In a machine of the character described, a bed, a movable die carrying head, a die carried by said head and movable with respect to said bed, infolding means, said bed and die and infolding means being adapted to cooperate to partially form an article, said die and head being adapted to remove and support the article after such partial formation, and means carried by said die head to indent the edge of the article when said die head is removed from said bed. 30

2. In a machine of the character described, a bed, a forming die adapted to be positioned on and removed from said bed, and means for indenting a blank of material on said die when said die is removed from said bed. 35

3. In a machine of the character described, a bed, a forming die movable toward and from said bed, and means for indenting a blank of material on said die when said die is moving from said bed. 40

4. In a machine of the character described, a bed, a forming die movable from and toward said bed, and means for marking a blank of material on said die when the die has moved from said bed. 45

5. In a machine of the character described, a movable die head, a forming die carried by said die head, and means associated with said die head and said forming die for making a plurality of indentations in a blank of material 50 carried by said die, said means being movable relatively to said die upon actuation of said die head.

6. In a machine of the character described, a bed, a die head movable toward and from the 55 bed, a forming die carried by said die head, and cooperating means associated with said die head and said forming die for indenting a blank of material carried by said die while the latter is removed from the bed.

7. In a machine of the character described, a material supporting bed, a die head movable toward and from the bed, a forming die carried by said die head, infolding means, said bed and forming die and infolding means operable to infold a blank of material, and means associated with said die head and said forming die for indenting a blank of material on the forming die while the forming die is removed from the bed. 65

8. In a machine of the character described, a die head, a forming die carried by said die head, a finger mounted on said die head, a recess in the edge of said forming die, and means operable to move said finger into said recess to indent the edge of a blank of material on said die. 70

5

20

30

35

40

45

50

60

65

70

75

9. In a machine of the character described, a bed, a forming die, means for moving said forming die toward and from said bed, and means operable by said first-named means to indent a blank of material on said die while the latter is removed from said bed. 5
10. In a machine of the character described, a bed, a forming die adapted to be positioned on and removed from said bed, and means for applying heat and pressure to a blank of material on said die to indent the same when said die is removed from said bed. 10
11. In a machine of the character described, a die head, a forming die carried by said die head, a finger mounted on said die head, a recess in said forming die, means for heating said finger, and means operable to move said finger into said recess to indent a blank of material on said die. 15
12. In a machine of the character described, 20 a die head, a forming die carried by said die head, a plurality of fingers mounted on said die head, a plurality of recesses in said forming die, and means operable to move said fingers into said recesses to indent the blank of material on said die at spaced points. 25
13. In a machine of the character described, a die head, a forming die section carried by said die head, a finger mounted on said die head, a recess in said die section, means for adjusting the position of said die section with respect to 30 said die head, and means for adjusting the position of said finger to align the same with said recess. 35
14. In a machine of the character described, a bed, a contractile forming die movable toward and from said bed, means for contracting said die as it is moved from said bed, and means for indenting a blank of material on said die when the same is moving from said bed, said indenting 40 means being operable when said die is in expanded condition. 45
15. The method of forming a blank of material which consists in infolding the edges over a forming die, and indenting the folded edge by applying heat and pressure to the edge at spaced points, the pressure being applied in a direction in the plane of said forming die and inwardly from the edge thereof. 50
16. In a machine of the character described, a forming die, means for forcibly indenting a blank of material on said die, and means for adjusting said first named means to vary the force applied by the same. 5
17. In a machine of the character described, a forming die, means for indenting the edge of a blank of material on said die by pressing it in a direction inwardly from the edge of said die, and means for adjusting said indenting means to vary the pressure applied to the blank. 10
18. In a machine of the character described, a die head, a forming die, means associated with said die head and said forming die for forcibly indenting a blank of material on said forming die, and means for adjusting said first-named means to vary the force applied to said blank. 15
19. In a machine of the character described, a die head, a forming die carried by said die head, a finger mounted on said die head, a recess in said forming die, means operable to move said finger into said recess to forcibly indent a blank of material on said die, and means for adjusting said finger to vary the force applied by the same to said blank. 20
20. In a machine of the character described, a die head, a forming die carried by said die head, a plurality of fingers mounted on said die head, a plurality of recesses in said forming die, means operable to move said fingers into said recesses to forcibly indent the blank of material on said die at spaced points, and means for adjusting said fingers for varying the force applied by the same to said blank. 25
21. In a machine of the character described, a bed, a contractile forming die adapted to be positioned on and removed from said bed, means for contracting said die when it is removed from said bed, and means for indenting a blank of material on said die when said die is removed from said bed, said indenting means being operable prior to said contracting means. 30
22. In a machine of the character described, a material supporting bed, a die head movable toward and from said bed, a contractile forming die carried by said die head, infolding means, said bed and forming die and infolding means operable to infold a blank of material, means for contracting said forming die when it is removed from said bed, and means associated with said die head and said forming die for indenting a blank of material on said forming die when said die is removed from said bed, said indenting means being operable prior to said contracting means. 40
